UNITED STATES PATENT OFFICE.

EDWIN F. HULBERT, OF SOUTH NORWALK, CONNECTICUT, ASSIGNOR TO NATIONAL PAPER CAN COMPANY, OF SOUTH NORWALK, CONNECTICUT, A CORPORATION OF DELAWARE.

EXPANDING DIE OR TOOL.

1,189,823.

Specification of Letters Patent.

Patented July 4, 1916.

Application filed May 21, 1914. Serial No. 839,995.

To all whom it may concern:

Be it known that I, EDWIN F. HULBERT, a citizen of the United States, residing at South Norwalk, in the county of Fairfield 5 and State of Connecticut, have invented a new and useful Improvement in Expanding Dies or Tools, of which the following is a full, clear, and exact description, reference being had to the accompanying drawings, 10 forming part of this specification, in which:

Figure 1 is a plan view showing one form of my improved expanding die or tool with the parts expanded. Fig. 2 is a cross section on the line II-II of Fig. 1. Figs. 3, 15 4 and 5 are detail views of the expanding wedges. Fig. 6 is a plan view of one of the expanding sections. Fig. 7 is a front view of the same. Fig. 8 is a view similar to Fig. 1, showing the parts in contracted position, and Figs. 9 and 10 are cross sections 20 similar to Fig. 2 showing other forms of the die or tool.

My invention relates to the securing of closures within the ends of cans or receptacles, and is designed to provide an expanding tool or die which will do away with the need for a supporting mandrel within the receptacle and will co-act with external dies to properly bead or shape the end portion 30 of the receptacle for co-action with the closure. The tool is also adapted to be used for securing the closure in place and is intended to act upon both the flange of the closure and the wall of the receptacle by 35 jointly beading them and co-acting with an end die and outside supporting anvils or dies.

The invention consists in an expanding die or tool which may be inserted within 40 the end of the receptacle, and preferably within the flange of the closure while in place within the end of the receptacle; the tube acting to bead and shape the end portion of the receptacle, together with the circular flange of the closure.

In the drawings, referring to the form of Figs. 1 to 8 inclusive, 2 represents a die segment, such as shown in Figs. 6 and 7. The external surface of this section or segment forms the arc of a circle and preferably has the step formation shown, although this may be varied according to the requirements of the other dies.

As shown, the lowest portion of largest diameter 3 forms a projecting lip adapted 55 to form a bead in the closure and end portion of the receptacle when the parts are expanded. The neck 4 is adapted to receive a portion of the seam when engaged by another end moving die moving at right 60 angles to the plane of the die or tool shown. Each segment is provided along its angular inner portions with cam recesses 5, which are engaged by the depending side lips or projections 6 of the wedges 7. Each wedge 65 has two of these depending lips, which lips engage each a cam groove of one of the arc-shaped segments of the die or tool. The outer projecting portion 8 of each wedge is shaped to correspond with the portions 3 70 and 4 of the segments so that when the parts are in expanded position, as shown in Fig. 1, a complete circular die is formed.

The dies and wedges are assembled, as shown in Fig. 8, the side portions of the 75 wedges preferably fitting against each other and as shown in Fig. 8 the segments are in their contracted positions. The parts in this position are inserted within the flange of a closure within the end of a receptacle 80 and an expanding device is then employed within the tool to expand the parts into the position shown in Fig. 1. In this expanding operation the desired beading effect is obtained upon the material, and the 85 portions 4 of the segments and corresponding portions 8 of the wedges act as dies to receive an endwise moving die or tool for shaping the seam between the closure and vessel, if desired. The tool is preferably 90 used in connection with a surrounding outer concentric angle or die which contracts in forming the bead.

In Figs. 9 and 10, I show tools corresponding to those shown in Figs. 1 to 8, except that the end portions 3^a and 3^b are modified to give successive operations in the forming of the complete seam closure between the cap and the body of the receptacle.

The device is preferably made in eight pieces, four segments and four wedges, as this gives sufficient expanding and contracting capacity, though a larger number may be used if desired. The construction is 105 strong and allows the exertion of heavy

pressures; the movements of the segments are positive in both directions by reason of the tongue and groove engagement of the wedges therewith, and the tool does away 5 with the need for inserting mandrels inside the receptacle beyond the cap.

Heretofore, such closures could only be seamed at one end of the receptacle on account of the necessary presence of the internal supporting mandrel, while my invention 10 enables the support to be applied at both ends, as the die is not within the receptacle body and no mandrel is needed. When expanded, a true circle is afforded, 15 thus giving the desired action at all points around the closure and body while the die can easily be contracted and withdrawn clear from the work being done.

The amount of movement may be increased 20 or decreased by varying the angle of the dove-tails or engaged cam grooves between the wedges and segments, and other variations may be made without departing from my invention.

25 I claim:

1. An expanding tool or die comprising a plurality of segments having external die portions and a plurality of intermediate wedges arranged to expand and contract 30 said segments, said parts having tongue and groove engagement to positively expand and contract the segments; substantially as described.

2. An expanding tool or die having at 35 least four segments, said segments each having external die portions, and at least four wedges coacting therewith to expand or contract the segments, each of said wedges also having external die portions, the external

die portions on the segments and wedges 40 when expanded forming a complete circle of similar contour; substantially as described.

3. An expanding tool or die having a series of segments with beading portions arranged to bead the wall of the receptacle or 45 closure, and wedges arranged to expand the segments and having edge portions similar to the segments and forming a continuation thereof when the parts are expanded; substantially as described.

4. An expanding tool or die, comprising a series of expanding segments each having an arc-shaped outer surface with angular inner portions, and a series of wedges co-acting therewith, said wedges having tongue and 55 groove engagement with the inner inclined portions of the segments and provided with outer portions shaped similar to the outer portions of the segments, the parts when expanded forming a complete circle of similar 60 contour throughout; substantially as described.

5. An expanding tool or die, comprising at least four segments, each having an outer shaping surface, combined with at least four 65 expanding wedges movable along angular portions of the segments and engaged therewith to positively move the same, the wedges having outer shaping surfaces corresponding to the outer shaping surfaces of the segments; substantially as described.

In testimony whereof, I have hereunto set my hand.

EDWIN F. HULBERT.
